Primary Examiner — Cynthia Ramirez*Assistant Examiner* — Michael A Maharajh(74) *Attorney, Agent, or Firm* — Trego, Hines & Ladenheim, PLLC; Brandon Trego; Jonathan Hines(57) **CLAIM**

I claim the ornamental design for a calf raise device, as shown and described.

DESCRIPTION

FIG. 1 is a perspective view of a calf raise device, showing my new design;

FIG. 2 is a front elevational view of the calf raise device of FIG. 1;

FIG. 3 is a rear elevational view of the calf raise device of FIG. 1;

FIG. 4 is a right side elevational view of the calf raise device of FIG. 1;

FIG. 5 is a left side elevational view of the calf raise device of FIG. 1;

FIG. 6 is a top plan view of the calf raise device of FIG. 1; and,

FIG. 7 is a bottom plan view of the calf raise device of FIG. 1.
